DESIGN FOR A SIGNAL LAMP FOR AUTOMOTIVE VEHICLES

Bornett L. Bobroff, Racine, Wis.

Application April 18, 1935, Serial No. 56,449

Term of patent 14 years

To all whom it may concern:

Be it known that I, Bornett L. Bobroff, a citizen of the United States, residing at Racine, in the county of Racine and State of Wisconsin, have invented a new, original, and ornamental Design for a Signal Lamp for Automotive Vehicles, of which the following is a specification, reference being had to the accompanying drawing, forming part thereof.

In the accompanying drawing, Figure 1 is a

face view of the signal lamp for an automotive vehicle.

Figure 2 is a top view of the signal lamp.

I claim:

The ornamental design for a signal lamp for automotive vehicles as shown.

In witness whereof, I have hereunto set my hand this 15th day of April, 1935.

BORNETT L. BOBROFF.
